AMPLIFYING SYSTEM

Original application filed July 26, 1924, Serial No. 728,280. Divided and this application filed January 19, 1925. Serial No. 333,633.

My invention relates to thermionic amplifiers and their associated circuits utilizable for amplifying fluctuating currents or oscillations, and more particularly currents of the character present in radio receiving apparatus.

This application is a division from my application Serial No. 728,280, filed July 26, 1924.

10 In accordance with my invention the stabilizing resistance or impedance of an amplifier system, comprising a thermionic amplifier or amplifier of the audion type having input and output circuits or systems including loops or closed circuits tunable throughout a range of wave lengths, is utilized as described in my prior application aforesaid, in one or more relations as follows:

(a) In one or more stages in each of which the input or output transformer, or both, has or have substantial step-up ratio; and the inductance effective in the plate or anode circuit is of relatively low magnitude.

(b) In one or more stages in each of which the input or output transformer, or both, has or have loose coupling between the primary and secondary circuits.

(c) In a plurality of stages in each of whose input circuits or systems substantially 30 the entire stabilizing resistance or impedance is connected in series between one terminal of the tunable loop and the grid, while the other terminal of the tunable loop is connected to, or is at substantially the same potential as that of, the cathode or filament.

(d) In one or more stages in each of which the stabilizing effect of the resistance or impedance is complementary or supplemental to the effect of additional means for reducing 40 or partially eliminating regeneration of feedback tending to contribute to production of oscillations.

(e) With a detector of the thermionic or audion type in whose input circuit or system 45 is a tunable loop external to which and in

series with the input electrodes is disposed the stabilizing resistance or impedance.

(f) With means for preventing substantial conduction between the grid and cathode structures within the related tube.

50 My invention resides in the features of structure, arrangement and proportionment hereinafter described and claimed.

For an understanding of my invention and for an illustration of one of the various forms it may take, reference is to be had to the accompanying drawing, which is a diagrammatic view of a radio receiving system.

55 The antenna D represents generically an antenna, a loop antenna or other structure for absorbing electro-radiant energy from the natural media, and represents also a circuit or path in or operatively related to an artificial conductor system extending between transmitting and receiving stations for transmitting signals, speech or controls by carrier 60 waves.

65 Between the antenna D and the earth or counter-capacity E is connected the primary of a radio frequency air-core transformer T, whose secondary is shunted by the variable tuning condenser C, which with said secondary comprises the tunable loop circuit per se whose electrical constants are such as to make it resonant with or sharply tunable 70 to the received high frequency energy. The thermionic device V, as a vacuum tube of the audion type, comprises as usual the anode a, grid or control electrode g and filament or cathode f, and has its input or grid 75 circuit connected to the aforesaid tuned circuit.

The anode and cathode at least are disposed in an envelope or tube evacuated to any suitable degree, and generally and preferably to that high degree effecting pure 80 electron discharge. It will be understood, however, that my invention is applicable to any suitable degree of vacuum, and is applicable also to those tubes containing gas.

85 The tube V operates as an amplifier, in 90

this example as a radio frequency amplifier, in whose anode circuit is connected the primary of a radio frequency air-core transformer T1 whose secondary constitutes an inductance shunted by the tuning condenser C1, which with its associated inductance constitutes a second resonant or tunable circuit or loop connected to or in the input circuit of a second amplifier V1, in whose anode circuit is the primary of a third radio frequency air-core transformer T2 whose secondary is a tuning inductance shunted by the tuning capacity C2 and forming therewith a tunable or resonant circuit or loop connected to or in the grid circuit of the detector tube V2, which may have characteristics similar to either of the tubes V, VI, or which may have different characteristics, as, for example, lower vacuum, suiting it to demodulating or detector purposes. In circuit with the grid is the grid condenser K shunted by the grid leak resistance r . In the anode circuit of the tube V2, which is not tuned, or is at most broadly tuned, is included the instrument I, which may be a telephone, loud speaker or generically, any translating device, as, for example, the primary of an audio frequency transformer for coupling the anode circuit of the tube V2 with the grid circuit of an audio frequency amplifier, which may be the first of any suitable number of stages of audio frequency amplification.

The cathodes f are heated by current from the battery A through the control rheostats H, by means of which a substantial amount of stabilization is effected or the tendency to production of oscillations is reduced. This stabilization or reduction of tendency to production of oscillations increases with increase of resistance H in the filament circuit.

The anode circuits include the battery or source of current B.

Between the anode a and grid g of a thermionic device of the audion type exists a capacity which couples or assists in coupling the output and input circuits to each other. This coupling capacity, indicated in dotted lines at C3, lends itself in effecting what may be a regenerative coupling between output and input circuits which in many cases causes the production locally of parasitic or undesired oscillations. The prevention or suppression of the regenerative coupling, and the prevention of the production of such oscillations are objects of my invention, which, in another aspect, relates to the reduction or annulment of the effect of the intra-tube coupling capacity.

In accordance with my invention, I introduce into one of the circuits, particularly the input or grid circuits or system, externally, however, to the tuned or resonant circuit or loop per se comprising the tuning

capacity condenser C, C1 or C2, and either in the filament or grid lead, but preferably, as indicated, in the grid lead, a resistance or impedance R, which may be a non-inductive resistance, or an impedance comprising resistance and some inductive reactance, though a strictly non-inductive or substantially non-inductive resistance is preferred.

By utilization of a resistance R of suitable magnitude, the regenerative action between output and input circuits of a tube is reduced or annulled, the production of undesired or parasitic oscillations is prevented, and in general, the coupling effect of the grid-to-anode capacity C3 is materially reduced or annulled as regards its action in assisting regenerative coupling between the output and input circuits of the tube.

The utilization of the resistance R prevents impression upon the associated grid g of a potential of such magnitude and phase relation as to encourage or induce regenerative action or as to cause the production of undesired oscillations, which, if present, cause squeals, howls or, in general, audible disturbances in instrument I.

The magnitude of the impedance or resistance R suitable for the purposes described should, from the aspect of its damping effect upon the tunable or resonant circuit or loop per se, be as small as possible to preserve to as great an extent as possible the sharp tuning qualities of that circuit, and, on the other hand, should be of a magnitude sufficiently great to reduce or eliminate the effect of regenerative action and production of oscillations.

The magnitude of the resistance or impedance R will be greater as the amplification factor of the associated tube or tubes is greater and as the grid-to-anode capacity, C3, is greater, and is greater as the reciprocal of the anode circuit resistance or impedance within the tube is greater, and particularly as the external impedance or resistance between the anode and cathode with respect to fluctuating or alternating current and as influenced to some extent by the anode-cathode capacity, is greater.

Tubes, even when of the same type or make vary among themselves as regards the magnitudes of their amplification factors grid-to-anode capacities, and plate circuit impedances, particularly their anode-to-cathode impedances; and furthermore, the relations of these factors vary with varying conditions under which the tubes are employed. In consequence, it is desirable that the magnitude of the resistance R be sufficiently high to suit a maximum value of the product of the amplification factor, grid-to-anode capacity and reciprocal of the internal anode circuit or anode-to-cathode impedance.

I have found that a suitable magnitude of

the resistance or impedance R in ohms is determinable from the expression:—

$$R = kmCP10^{-8},$$

in which, m is the amplification factor, C the grid-to-plate capacity in micro-micro-farads, k is a factor of the order of 4 for two or more amplifier tubes in cascade, and P the impedance of the plate circuit external to the tube.

Taking, for example, a UV 201—A tube now upon the market, whose grid-filament capacity is of the order of 6 micro-micro-farads, and for which m is 8, C is 6, and with P 3000 ohms, R for each of the stages should be given a magnitude of the order of 550 to 650 ohms. For these conditions stated, a resistance R of this magnitude will prevent production of the undesirable oscillations and reduce or suppress the effect of inherent regenerative action, and yet will not materially affect the sharpness of tuning of the tunable or resonant circuit or loop per se comprising any of the condensers C, C1 and C2 with its associated inductance, which is in the example illustrated, a secondary of a radio frequency transformer and of fixed magnitude. However, UV 201—A tubes vary among themselves as to the aforesaid factors, and to take care of variations consisting in increases in the amplification factor and grid-to-anode capacity and increase in the impedance P, the resistance R is in practice preferably given a magnitude greater than its aforesaid value, but not sufficiently greater seriously to affect the sharp tuning or resonance qualities of the tunable circuit or loop per se.

In case of employment of but a single radio frequency amplifier tube, as distinguished from the cascade or staged relation above referred to, the impedance or resistance R will have a magnitude preferably of the order of twice that given by the foregoing empirical formula and example.

The use of the resistance R in the input circuit of a detector tube, as V2, and in other relations where currents of radio or audio frequency are to be amplified, is of advantage notwithstanding there may not be present sharp resonance or tuning, as in the case of the anode circuit of the detector tube which is not sharply tuned but is at best broadly tuned. The utilization of the resistance R, however, finds its principal application in the input circuits of tubes, such as V and V1, used simply as radio frequency amplifiers.

It is preferred, as to each of the input circuits with which the resistance R is associated, that the grid g be negative, or at any rate not sufficiently positive to effect substantial conductivity between grid and cathode f. In the example illustrated this is effected by connections of the grid circuits to those terminals of cathodes f which are connected to the negative terminal of the A battery.

This effects substantially pure capacity between the input electrodes g and f; and avoids substantial conduction between them which would produce damping, of the tunable circuits, of a less desirable relation with respect to frequency than is afforded by resistances R in series with small substantially pure capacities.

It is further preferable that for the wave lengths for which the receiving apparatus is to be utilized, or throughout a part or whole of a range of different wave lengths for which it is to be utilized, the inductance associated with each of the condensers C, C1 and C2 and constituting the secondary of the transformers T, T1 and T2 shall be the predominating frequency-determining element of the tuned circuit or loop per se in the sense that such inductance is large compared with the associated tuning capacity, whereby the persistency of each tuned circuit is high or its decrement is small, with the result that such damping effect as the resistance R may have upon the tuned circuit is suitably small.

For example, for a wave length range of the order of from 200 to 600 meters, the secondary of each of the transformers T, T1 and T2 may have an inductance of the order to .3 millihenry, and each of the associated tuning capacities C, C1 and C2 may have a magnitude varying from about .00003 micro-farad for 200 meters to about .00027 for 600 meters. From these relations it will be noted of each product LC that the factor L greatly predominates.

The mutual inductance between the primary and secondary of each of the transformers T, T1 and T2 may be of the order of .025 millihenry and the coupling co-efficient of the order of 30 per cent.

The proportions of the order and character above stated with respect to the coupling transformers involve step-up ratios of turns and voltage, and in the example given, the inductance of the primary is of the order of .02 or .03 millihenry, the step-up of voltage is of the order of 1 to 10, the secondary voltage being of the order of ten times that of the primary. Furthermore the coupling between primary and secondary windings is loose, in the sense that it is substantially and materially less than unity or very close coupling.

A fixed inductance, as a winding of a coupling transformer, with its variable condenser constitutes a closed or loop circuit tunable throughout a wave length range and comprised in an input or output system; and across the terminals of the inductance or the tuning condenser are connected the cathode and one of the other electrodes of a tube. The resistance R is external to the tuned loop. This particular position of the resistance, external to the tuned loop or circuit, in series with the small capacity between grid

and cathode, in a path in shunt to the loop, is of importance and advantage, as distinguished from connection of the resistance in series within the tunable closed or loop circuit, or of resistance in shunt to the loop without the small capacity. By the external shunt connection of the resistance in series with small capacity it becomes markedly effective in reducing the tendency to increased instability with increasing frequency, with the input and output systems tunable, as shown, by fixed inductance and variable capacity. This is in marked contrast with the behavior of a fixed resistance in series in the grid circuit, external to the tube, but in series in the tunable loop or closed circuit, where the stabilizing or damping effect of the resistance is constant for all frequencies to which the loop or closed circuit is tuned. When the stabilizing resistance or impedance R is connected in series in the grid circuit, external to the tube, in a position where it is also external to the tunable closed circuit or loop and in series with the small capacity formed by the grid and cathode, its effect upon the closed circuit or loop for any frequency to which it is tuned is inversely proportional to the square of the magnitude of the capacity which tunes the loop or closed circuit at that frequency, or is proportional to the fourth power of the frequency to which the loop or closed circuit is tuned. Notwithstanding the resistance R is not varied or is of fixed magnitude, its effect varies automatically in proportion to the fourth power of the frequency when in the described position and in series with the small capacity formed by the grid and cathode. To procure the same effect by resistance in series in the tunable loop or closed circuit, requires an adjustment very rapidly increasing the magnitude of the resistance with increase in frequency. The regenerative effect, or the negative resistance introduced by regenerative action into the tuned grid circuit, is proportional to the fourth power of the frequency. The effect of positive resistance R accordingly rapidly increases at the same rate of increase of the aforesaid negative resistance with increase of frequency to which the system is tuned, and resistance R , in the relation described, is well suited to oppose or compensate for regenerative effects. When the tuning capacity is large for the low frequency portion of the wave length range where the tendency to instability is small, the effect of the externally connected resistance R and small grid-cathode capacity is small, while when the tuning capacity is of low magnitude, for the high frequency portion of the wave length range, where the tendency to instability is great, the effect of the externally connected resistance R in series with small inter-electrode capacity is very great. Throughout the wave length

range to which the system is tunable the reactance of the small capacity, in series with the stabilizing resistor R , preponderates over or is high relatively to the resistance of the resistor R .

By cooperation with the stabilizing resistance R , positioned and having the effect described, other features hereinbefore described are of advantage by way of reducing the stabilizing effects of other resistances inherent in the system and which are proportional to lower powers of the frequency than the aforesaid fourth power effect of the resistance R .

Because of the loose coupling, and more particularly because of the substantial step-up ratio, of the transformer T , which couples the absorption structure or antenna system DE to the input circuit of the tube V , the damping effect of the absorption structure or antenna system upon the input circuit or tunable loop of the input system of the tube V , is materially reduced. In consequence, the damping produced by the resistor R is a greater proportion of the total damping effective in the loop tunable by condenser C .

Similarly, by reduction of the damping of the tube V or V_1 upon the tunable loop of the input system of the tube to which its anode circuit is coupled, and by reduction of the damping effected by prevention of substantial conduction between grid and cathode, both about to be described, the damping produced by resistor R becomes a greater proportion of the total damping effective in the tunable loop to which it is related.

Because of the loose coupling, and particularly because of the high step-up ratio, of the transformer T_1 or T_2 , the damping effect upon the tunable loop in the input circuit of the tube V_1 or V_2 due to the resistance of the tube V or V_1 , particularly within it between its anode a and cathode f , is greatly reduced, and the damping produced by the resistor R becomes a greater proportion of the total damping effective in the tunable loop of the circuit or system with which resistor R is related. Such resistance transferred by the transformer T_1 or T_2 to the loop tunable by the condenser C_1 or C_2 , is equivalent to a resistance in series within the loop tunable by C_1 or C_2 whose damping effect is proportional to the square or second power of the frequency. By the loose coupling or substantial step-up ratio aforesaid, the damping effect proportional to the second power of the frequency is materially reduced, and in consequence the stabilizing effect of the resistance R plus that of the internal resistance of the preceding tube between its anode and cathode remains more nearly proportional to the fourth power

of the frequency, characteristic of the stabilizing effect of the resistance R alone.

Resistance within the tube, such as might be due to conduction from the grid g to the cathode f , is not, though external to the tuned loop of the input system, in series with a small capacity, and in consequence its stabilizing effect is also the equivalent of that of a resistance in series in the tuned loop and whose effect varies with the square of the frequency. By reducing such inter-electrode conduction within the tube, the total of its effect plus that of the resistance R remains more nearly proportional to the fourth power of the frequency, characteristic of the resistance R alone. In the present case the inter-electrode conduction, as that between the grid g and cathode f of a tube, is made inconsequential or negligible by the aforesaid negative bias of the grid g with respect to the filament or cathode f .

The regenerative action, through the anode-grid capacity to which the magnitude of resistance R is proportional, is reduced or limited by the low effective inductance in the anode circuit of the tube, as effected by the low inductance of the primary winding, particularly when in or of a transformer of loose coupling and high step-up ratio. The stabilizing effect of resistance R is supplemented by another stabilizing effect procured by the resistance or rheostat H by which the cathode-heating current may be graduated or controlled, by inclusion in the filament circuit of suitable amount of the resistance H ; the greater the amount of the resistance H in circuit with its filament f the smaller is the regenerative effect or feed-back action, and the greater the stabilizing effect by filament current control. The low anode circuit inductance and control of filament or cathode current individually and jointly complement or supplement the stabilizing effect of the resistance or impedance R , in procuring a stable or non-oscillating amplifier system.

In a multistage system, such as hereinbefore described, the filaments or cathodes f are generally grounded, and the rotors or adjustable elements of the tuning condensers are those plates or armatures of the tuning condensers which are connected to the cathodes or grounded. To maintain this arrangement substantially the entire stabilizing resistance R in each stage is disposed in the connection from the other armature or plate of the tuning condenser to the grid g . With the entire or a substantial part of the total resistance R of a stage connected between the lower terminal of the tuned loop and the filament or cathode f , the lower plate or armature of the tuning condenser, generally the rotor as stated, will be at a potential substantially different from that of the cathode, which is undesirable for the well-known rea-

son that approach of the hand of the operator to the adjustable element or armature of the tuning condenser has less effect when that plate or armature is at substantially the potential of the grounded cathode or filament 70 than when it is at a substantially different potential.

For brevity in the appended claims the term "resistance" is used in a generic sense to include non-inductive resistance and resistance which may be more or less inductive. 75

What I claim is:

1. The combination with a thermionic amplifier, of an input system therefor tunable throughout a range of frequencies by fixed 80 inductance and a variable condenser effectively in shunt therewith to form a tunable loop, an output system tunable throughout said range of frequencies by a fixed inductance with a variable condenser effectively 85 in shunt therewith, a capacitative coupling between said output and input systems, the tendency of the amplifying system to become unstable increasing as said input and output systems are tuned to higher and higher frequencies 90 of said range, the inductance effective in the anode circuit of said amplifier having relatively low magnitude, and a resistance in one of said systems external to the tunable loop thereof and in series with 95 a small capacity, whereby the aforesaid tendency of the amplifying system to instability is compensated for by said resistance whose stabilizing effect rapidly increases with increase of frequency. 100

2. The combination with a thermionic amplifier, of an input system therefor comprising a loop tunable throughout a range of frequencies, an output system comprising a loop tunable throughout said range of frequencies, a capacitative coupling between 105 said output and input systems, the tendency of the amplifying system to become unstable increasing as said loops are tuned to higher and higher frequencies of said range, means for preventing substantial conduction between the input electrodes of said amplifier, a fixed resistance external to the tunable loop of said input system and in series with said input electrodes, whereby the stabilizing effect of said resistance rapidly increases with increase in frequency, and supplemental means limiting the regenerative action between said output and input systems through 110 said capacitative coupling. 115

3. The combination with a thermionic amplifier, of an input system therefor comprising a loop tunable throughout a range of frequencies, an output system comprising a loop tunable throughout said range of frequencies, a capacitative coupling between said output and input systems, the tendency of the amplifying system to become unstable increasing as said input and output systems are tuned to higher and higher frequencies of 125 130

said range, the inductance effective in the anode circuit of said amplifier having relative low magnitude, a resistance in one of said systems external to the tunable loop thereof and in series with a small capacity, whereby the aforesaid tendency of the amplifying system to instability is compensated for by said resistance whose stabilizing effect rapidly increases with increase of frequency, and supplemental means for limiting the regenerative action between said output and input systems through said capacitative coupling.

4. The combination with a thermionic amplifier, of an input system therefor tunable throughout a range of frequencies by fixed inductance and a variable condenser effectively in shunt therewith to form a tunable loop, an output system tunable throughout said range of frequencies by a fixed inductance with a variable condenser effectively in shunt therewith, a capacitative coupling between said output and input systems, the tendency of the amplifying system to become unstable increasing as said input and output systems are tuned to higher and higher frequencies of said range, a resistance in said input system external to the tunable loop thereof and in series with a small capacity, whereby the stabilizing effect of said resistance rapidly increases with increase in frequency, a system traversed by current to be amplified, and a loose coupling between said last named system and said input system for reducing the damping effect thereof upon said input system, whereby the proportion of the total damping effect produced by said resistance is increased.

5. The combination with a thermionic amplifier, of an input system therefor comprising a loop tunable throughout a range of frequencies, an output system comprising a loop tunable throughout said range of frequencies, a capacitative coupling between said output and input systems, the tendency of the amplifying system to become unstable increasing as said input and output systems are tuned to higher and higher frequencies of said range, a fixed resistance in said input system external to the tunable loop thereof and in series with a small capacity, whereby the stabilizing effect of said resistance rapidly increases with increase in frequency, a second thermionic device, and means for loosely coupling the output circuit of said device to said input system to reduce the damping effect of said device upon said input system, whereby the proportion of the total damping effect produced by said resistance is increased.

6. The combination with a thermionic amplifier, of an input system therefor comprising a loop tunable throughout a range of frequencies, an output system comprising a loop tunable throughout said range of frequen-

cies, the tendency of the amplifying system to become unstable increasing as said input and output systems are tuned to higher and higher frequencies of said range, a resistance in said input system external to the tunable loop thereof and in series with a small capacity, whereby the stabilizing effect of said resistance rapidly increases with increase in frequency, an antenna system, and means for loosely coupling said antenna system to said input system to reduce the damping effect thereof upon said input system, whereby of the total damping effect the proportion produced by said resistance is increased.

7. The combination with a thermionic amplifier, of an input system therefor comprising a loop tunable throughout a range of frequencies, an output system comprising a loop tunable throughout said range of frequencies, the tendency of the amplifying system to become unstable increasing as said input and output systems are tuned to higher and higher frequencies of said range, resistance in said input system external to the tunable loop thereof and in series with a small capacity, whereby the stabilizing effect of said resistance rapidly increases with increase in frequency, a system traversed by current to be amplified, and means for increasing the proportion of the total damping effect produced by said resistance comprising a magnetic coupling of substantial step-up ratio between said last named system and said input system.

8. The combination with a thermionic amplifier, of an input system therefor comprising a loop tunable throughout a range of frequencies, an output system tunable throughout said range of frequencies, the tendency of the amplifying system to become unstable increasing as said input and output systems are tuned to higher and higher frequencies of said range, a resistance in said input system external to the tunable loop thereof and in series with a small capacity, whereby the stabilizing effect of said resistance rapidly increases with increase in frequency, a second thermionic device, and means for increasing the proportion of the total damping effect produced by said resistance comprising a magnetic coupling of substantial step-up ratio between the anode circuit of said device and said input system.

9. The combination with a thermionic amplifier, of an input system therefor comprising a loop tunable throughout a range of frequencies, an output system tunable throughout said range of frequencies, in shunt therewith, the tendency of the amplifying system to become unstable increasing as said input and output systems are tuned to higher and higher frequencies of said range, a resistance in said input system external to the tunable loop thereof and in series with a small capacity, whereby the stabilizing effect of

said resistance rapidly increases with increase in frequency, an antenna system, and means for increasing the proportion of the total damping effect produced by said resistance comprising a magnetic coupling of substantial step-up ratio between said antenna system and said input system.

10. The combination with a thermionic amplifier, of an input system therefor comprising a loop tunable throughout a range of frequencies, an output system tunable throughout said range of frequencies, a capacitative coupling between said output and input systems, the tendency of the amplifying system to become unstable increasing as said input and output systems are tuned to higher and higher frequencies of said range, a resistance in said input system external to the tunable loop thereof and in series with a small capacity, the stabilizing effect of said resistance rapidly increasing with increase of frequency, a system traversed by current to be amplified, a magnetic coupling of substantial step-up ratio between said last named system and said input system, a transformer of substantial step-up ratio whose primary is in the anode circuit of said amplifier, the inductance effective in the anode circuit of said amplifier having relatively low magnitude, and supplemental means limiting the regenerative action between the output and input circuits through said capacitative coupling.

11. The combination with a thermionic amplifier, of an input system therefor comprising a loop tunable throughout a range of frequencies, an output system tunable throughout said range of frequencies, a capacitative coupling between said output and input systems, the tendency of the amplifying system to become unstable increasing as said input and output systems are tuned to higher and higher frequencies of said range, a resistance in said input system external to the tunable loop thereof and in series with the input electrodes of said amplifier, means preventing substantial conduction between said input electrodes of said amplifier, the stabilizing effect of said resistance rapidly increasing with increase of frequency, a system traversed by current to be amplified, a magnetic coupling of substantial step-up ratio between said last named system and said input system, a transformer of substantial step-up ratio whose primary is in the anode circuit of said amplifier, the inductance effective in the anode circuit of said amplifier having relatively low magnitude, and supplemental means limiting the regenerative action between the output and input systems through said capacitative coupling.

12. The combination with a thermionic detector, of an inductive output system therefor, an input system therefor including a tunable loop comprising inductance

and a variable condenser effectively in shunt therewith, and a fixed resistance in said input system external to the tunable loop thereof and in series with a small capacity for producing a stabilizing effect which rapidly increases with increase in frequency.

13. The combination with a thermionic amplifier, of an input system therefor comprising a loop tunable throughout a range of frequencies, an output system tunable throughout said range of frequencies, the tendency of the amplifying system to become unstable increasing as said input and output systems are tuned to higher and higher frequencies of said range, a resistance in said input system external to the tunable loop thereof in series with the input electrodes of said amplifier, and whose damping effect upon said tunable loop rapidly increases with increase in frequency, a system traversed by current to be amplified, and means for increasing the proportion of the total damping effect produced by said resistance comprising a loose coupling between said last named system and said input system, supplemented by means preventing substantial conduction within said amplifier between its said input electrodes.

14. The combination with a thermionic amplifier, of an input system therefor comprising a loop tunable throughout a range of frequencies, an output system tunable throughout said range of frequencies, the tendency of the amplifying system to become unstable increasing as said input and output systems are tuned to higher and higher frequencies of said range, a resistance in said input system external to the tunable loop thereof in series with the input electrodes of said amplifier, and whose damping effect upon said tunable loop rapidly increases with increase in frequency, a system traversed by current to be amplified, and means for increasing the proportion of the total damping effect produced by said resistance comprising a magnetic coupling of substantial step-up ratio between said last named system and said input system, supplemented by means preventing substantial conduction within said amplifier between its said input electrodes.

15. The combination with a thermionic amplifier, of an input system therefor comprising a loop tunable throughout a range of frequencies, an output system comprising a loop tunable throughout said range of frequencies, the tendency of the amplifying system to become unstable increasing as said loops are tuned to higher and higher frequencies of said range, a resistor of fixed resistance external to the tunable loop of one of said systems in series with a capacity, the magnitude of whose reactance at the frequencies of said range preponderates over the magnitude of said resistance, whereby the stabilizing effect of said resistor rapidly in-

creases with increase in frequency, an associated system, and a coupling of substantial step-up ratio coupling said one of said systems to said associated system.

- 5 16. The combination with a thermionic amplifier, of an input circuit therefor comprising a loop tunable throughout a range of frequencies, an output circuit comprising a loop tunable throughout said range of frequencies, the tendency of the amplifying system to become unstable increasing as said loops are tuned to higher and higher frequencies of said range, stabilizing means external to the tunable loop of one of said circuits comprising resistance in combination with a reactive element of the same kind as that which is variable to tune the loop of said one of said circuits, the stabilizing effect of said resistance and reactive element varying at a rate greater than the second power of the frequencies to which said input and output circuits are tuned, an associated circuit, and a magnetic coupling of substantial transformation ratio between said one of said circuits and said associated circuit.
- 10 17. The combination with a thermionic amplifier, of an input system therefor comprising a loop tunable throughout a range of frequencies, an output system tunable throughout said range of frequencies, stabilizing means external to the tunable loop of said input system comprising resistance in combination with a reactive element of the same kind as that which is variable to tune the loop of said input system, the stabilizing effect of said resistance and reactive element rapidly varying at a rate greater than the second power of the frequencies to which said input and output systems are tuned, a system traversed by current to be amplified, and means for increasing the proportion of the total damping effect produced by said stabilizing means comprising a magnetic coupling of substantial step-up ratio between said last-named system and said input system.

- 15 18. The combination with a thermionic amplifier, of an input circuit therefor comprising a loop tunable throughout a range of frequencies, an output circuit comprising a loop tunable throughout said range of frequencies, only the tuning elements of said input and output circuits being variable, the tendency of the amplifying system to become unstable increasing as said input and output systems are tuned to higher and higher frequencies of said range, stabilizing means external to the tunable loop of one of said circuits comprising resistance in combination with a reactive element of the same kind as that which tunes the loop of said one of said circuits, the effect of said stabilizing means varying at a rate greater than the second power of the frequencies to which said input and output circuits are tuned, an associated circuit, and a magnetic coupling of substan-

tial transformation ratio between said one of said circuits and said associated circuits.

19. The combination with a thermionic amplifier, of input and output systems therefor tunable throughout a range of frequencies, the tendency of the amplifying system to become unstable increasing as said input and output systems are tuned to higher and higher frequencies of said range, stabilizing means whose effect varies at a rate greater than the second power of the frequencies to which said input and output systems are tuned, and means for reducing stabilizing effect which is inherent in the amplifier system and which varies at a rate proportional to a power lower than the second power of the frequencies to which said input and output systems are tuned.

20. The combination with a thermionic amplifier, of an input system therefor tunable throughout a range of frequencies by fixed inductance and a variable condenser effectively in shunt therewith to form a tunable loop, an output system tunable throughout said range of frequencies by a fixed inductance with a variable condenser effectively in shunt therewith, a capacitative coupling between said output and input systems, the tendency of the amplifying system to become unstable increasing as said input and output systems are tuned to higher and higher frequencies of said range, the inductance effective in the anode circuit of said amplifier having relatively low magnitude, and a resistance in one of said systems external to the tunable loop thereof and in series with an inter-electrode capacity, whereby the aforesaid tendency of the amplifying system to instability is compensated for by said resistance whose stabilizing effect varies substantially as the fourth power of the frequency to which said input and output systems are tuned.

21. The combination with a thermionic amplifier, of an input system therefor comprising a loop tunable throughout a range of frequencies, an output system comprising a loop tunable throughout said range of frequencies, the tendency of the amplifying system to become unstable increasing as said loops are tuned to higher and higher frequencies of said range, a fixed resistance external to the tunable loop of said input system in series with a small capacity, whereby the stabilizing effect of said resistance varies substantially as the fourth power of the frequencies to which said loops are tuned, and supplemental means limiting the regenerative action between said output and input systems through said capacitative coupling.

22. The combination with a thermionic amplifier, of input and output systems therefor tunable throughout a range of frequencies, the tendency of the amplifying system to become unstable increasing as said input

and output systems are tuned to higher and higher frequencies of said range, stabilizing means included in one of said systems whose effect varies at a rate greater than the second power of the frequencies to which said input
5 and output systems are tuned, and means for reducing stabilizing effect introduced into said one of said systems by coupling to an adjacent system, which stabilizing effect varies at a rate proportional to a power lower
10 than the second power of the frequencies to which said input and output systems are tuned.
